C. L. OLIN

EXPANSION VALVE

Filed August 7, 1923

FIG. 1

FIG. 2

INVENTOR

CARL L. OLIN

BY

Harry R. Schneider
ATTORNEY

UNITED STATES PATENT OFFICE.

CARL L. OLIN, OF OAKLAND, CALIFORNIA.

EXPANSION VALVE.

Application filed August 7, 1923. Serial No. 656,280.

My invention is an improved expansion valve, particularly applicable to refrigerator systems in which a liquid under high pressure is allowed to expand into a vapor through the valve into cooling coils.

The object of my invention is to provide a novel, automatic controlling means for the needle valve, which will close said valve when the pressure is equalized on both sides of the expansion valve. To accomplish the above results I provide an expansion valve with a body portion having a high pressure inlet port at one side and outlet port at the opposite side, a vertical bore in the bottom of the valve body contains a sliding block with a pin which is adapted to open and close a passage from the inlet port. A duct leads from this bore to the outlet port and a pair of ducts from the outlet port to the under side of the diaphragm and to the under side of a plate resting against the bottom of the diaphragm. The diaphragm itself is mounted between the main body and a cap and may be tensioned by means of a spring. A pair of pins fixed to the block loosely edge the plate which bears against the diaphragm and hence control the opening and closing of the inlet passage and thence of the valve. Other novel objects and advantages will be more specifically described in the following detailed description.

In the annexed drawing in which my invention is illustrated—

Figure 1 is a transverse sectional view of my expansion valve.

Figure 2 is a sectional view taken on the line 2—2 of Figure 1.

Referring more particularly to the drawing, my expansion valve consists of a body 1 in which is formed a high pressure inlet port 2 and an outlet port 3. A vertical bore 4 is formed in the bottom of the body 1 and extends upwardly adjacent the ports 2 and 3. This bore is adapted to receive a block 5 which reciprocates therein and carries a needle 6 which is adapted to enter a passage between the port 2 and bore 4, thus forming a needle valve 7, as will be further described. A port 8 extends from the bore 4 to the port 3, through which the liquid expands into the cooling coils.

A diaphragm 9 is positioned in the upper part of the body 1 and is held in position by a cap 10 which threads into the body against the diaphragm. A spring 11 is positioned in the cap 10 and bears against the diaphragm 9 to urge it downwardly. The spring 11 is adjusted by a screw 12, which bears upon a plate 13 against the bottom of which plate the spring is positioned.

A cup 14 is threaded to the bottom of the body 1 and a spring 15 is positioned in the cup and bears against the block 5 to urge it upwardly.

A plate 16 rests against the bottom of the diaphragm 9 and is held in position by a pin 17 which depends from the bottom thereof and reciprocates in a bore 18 in the body 1. Pins 19 and 20 are secured in the block 5 and extend upwardly through the body 1 and rest against the bottom of the plate 16. Ducts 21 and 22 extend from the port 3 to the bore 18 and under the diaphragm 9 respectively, thus equalizing the pressure on both sides of the plate 16.

The operation of my invention is as follows: With the refrigerating machinery running, and a low pressure on the port 3 the diaphragm 9 will be depressed which will lower the plate 16 and consequently move the block 5 and needle 6 downwardly through the medium of the pins 19 and 20, thus opening the valve 7 and permitting the escape of the fluid coming into the port 2. When the machine shuts down and the pressure is equal in the ports 2 and 3, the diaphragm 9 rises and the block 5 and needle 6 are raised by the spring 15 to close the valve 7.

Having described my invention, I claim:

An expansion valve comprising a body portion having an inlet port and an outlet port, a central bore extending downwardly below said ports, a block slidably mounted in said bore, and a needle carried thereby, a passage leading from the inlet port to said bore and adapted to be closed by said needle, a cap secured to the upper portion of said valve body, a diaphragm clamped between the cap and the valve body, a coiled spring within said cap adapted to urge said diaphragm downwardly, a small bore within

said valve body, a loose plate having a pin formed integral therewith, said pin being slidable in the said small bore, a duct leading from the large bore to the outlet port, 5 ducts leading from the outlet port to the small bore and to the top of the valve body, and pins connected to said block and slidable in the valve body and adapted to contact with said loose plate, a second spring to re-

silently elevate said block and thereby hold 10 the loose plate in contact with the dia-phragm, and a cup having a screw threaded engagement to the lower end of the valve body and adapted to form a seat for said second spring. 15

In testimony whereof I affix my signature.

CARL L. OLIN.
